(57) **CLAIM**

I claim the ornamental design for a whisk, as shown and described.

DESCRIPTION

FIG. 1 is a top frontal left side perspective view of a whisk showing my design;

FIG. 2 is a bottom rear right side perspective view thereof; FIG. 3 is a right side elevational view thereof; and, FIG. 4 is a top plan view thereof.

The broken lines are for illustrative purposes only and form no part of the claimed design.
